JET BOX

Ernest J. Griset, Jr., Asheville, N. C., assignor to American Enka Corporation, Enka, N. C., a corporation of Delaware

Application October 27, 1954, Serial No. 465,019

4 Claims. (Cl. 68—181)

This invention relates to continuous spinning of rayon yarn and more particularly to improvements in the art of tube spinning of the type described in Griset application, Serial No. 122,560, filed October 20, 1949, now Patent No. 2,725,276 of November 29, 1955, and commonly owned herewith.

In the Griset application, mentioned above, there is disclosed an arrangement for the after treatment of rayon yarn that involves introducing the freshly spun yarn into a tube through which the yarn is propelled by a liquid which also effects a treating operation. After leaving the tube, the yarn is introduced successively into other tubes which are so arranged that the yarn runs back and forth through the necessary number of tubes required to effect the desired after treatment. The liquid in each tube is introduced by a jet spaced from the tube mouth in such a way as to define a low pressure zone through which yarn is entrained for propulsion and treatment by the liquid. Yarn ejected from the exit end of each tube is guided by a deflector to a position close to the low pressure zone of the next tube. Once the yarn is spun in, the establishment of a common path for both liquid and yarn from the exit end of one tube to the mouth of the next is undesirable and accordingly the deflectors are made to be movable to and from the pathway establishing position.

In commercial operations the various glass tubes of the system occasionally become clogged or broken with a resulting requirement for replacement. To this end the tubes in which the yarn is after treated have been arranged in cradles as shown in application Serial No. 341,529, filed March 10, 1953, now Patent No. 2,724,956 of November 29, 1955, and commonly owned herewith. By the use of these cradles it is possible to replace tubes with very minor interruption in the spinning operation and very small disassembly of the apparatus.

The original spinning of the yarn to the system of tubes is accomplished by leading the freshly-formed thread to the top of a deflector, washing it with water through the deflector channel to the low pressure zone of the first jet-venturi of the system. The thread is then sucked into the system. This part of the spinning system is a little different from the rest because, instead of spinning in and thereafter treating the thread with a liquid, the water which is used to wash the freshly spun thread into the first jet-venturi is shut off once the yarn is running in the tube system. Nevertheless, in these boxes the nozzles clog and breakage does occur and it has therefore required about fifteen minutes' time to make a replacement of a jet-tube unit in the first box of the system, commonly called the spinning in box. Furthermore, observation of the spinning in nozzle has been exceedingly difficult and leakage has been difficult to control.

It is an object of this invention to overcome the difficulties of the prior art and to provide a spinning in box for a tube spinning system which is characterized by ready manual and visual access to the jet-tube unit parts

2

whereby, in the event of damage to or clogging of a jet or tube, repair can be quickly and conveniently undertaken without major disassembly of the system.

Other objects and advantages of this invention will be apparent upon consideration of the following detailed description of a preferred embodiment thereof in conjunction with the annexed drawings wherein:

Figure 1 is a view in side elevation of a spinning in box constructed in accordance with the principles of the present invention;

Figure 2 is a plan view of the spinning in box of Figure 1; and

Figure 3 is an end view of the spinning in box of Figure 1 showing in broken lines the hinged side wall in its extended position.

The spinning in box 10, according to the present invention, is a long narrow structure having a large internal cavity 11, the bottom defining wall of which slopes from left to right as viewed in Figure 1 toward a drain outlet 12. Within the bottom of the box 10 there is mounted a lead bracket or saddle 13 having a supporting stem 14 removably seated in a socket in the bottom of the box 10, an arm 15 which supports a jet or tube 16 having a nozzle formed at one end and an arm 17 which supports a glass tube 18 having a flared mouth 19. The tubes 16 and 18 are commonly called a jet-tube unit. The arms 15 and 17 are so located that the jet 16 is in axial registry with the flared mouth 19 of the tube 18, but spaced from it axially a small but appreciable distance.

When a liquid is supplied through the jet tube 16 it enters the tube 18. This creates a suction zone around the mouth 19 and thread is introduced into the system by bringing it into proximity with this low pressure zone. To this end a deflector 20 is provided having a central channel at 21 connecting the outlet of a spigot 22 with the low pressure zone adjacent the flared mouth 19 of the tube 18. The spigot 22 supplies water which washes freshly spun yarn into channel 21 and along the channel to the venturi. The leftover liquid falls into the bottom of the box 11 and drains out the outlet 12.

The foregoing description involves no material new to this application but is necessary as a background in order that the improvements constituting the present invention may be understood. While the deflector 20 is similar in appearance to the corresponding parts shown in earlier applications of this applicant, the mounting of the deflector is entirely new. It will be noted that ears 23 and 24 extend from the side wall of the box 10 on the left hand side thereof as it appears in Figure 3. Through these ears 23 and 24 there extends a hinge pin 25 which receives thereover ears 26 and 27 which extend outwardly from plate 28. By this arrangement it can be seen that the plate 28 is hinged to move from the full line to the broken line position depicted in Figure 3. Fastened to the inner wall of the plate 28 by two screws 29 is the deflector 20. Thus, when the plate 28 is swung out to the broken line position of Figure 3, the deflector moves with it and in so doing affords easy access both visual and manual to the tube 16 which lies below the deflector as can be seen from Figure 2.

An ordinary cylindrical porcelain thread guide 30 passes through the wall 28 and through a corresponding wall 31 on the right side of the box 10 as it is viewed in Figure 3. The wall 31 is stationary and when rubber washers 32 and 33 are placed over the ends of guide 30, hinged wall 28 is held in its upright position from wall 31 through guide 30 but it is held in a way which renders disconnection and movement thereof very easy.

Of course once the yarn path to the mouth 19 of the tube 18 has been established and the yarn is running in the system it will no longer occupy the channel 21 of the deflector 20. Instead it will pull up to the broken line

position of Figure 1 passing under the thread guide 30 and from there into the mouth 19.

In the event of clogging of the jet 16 all the operator needs to do is to remove one of the washers 32—33, slip out the guide 30, swing the side 28 to the broken line position in Figure 3, and lift out the assembly including tube 16, tube 18 and saddle 13. The tube 16 is held in a resilient U member 34 at the left hand end of the box 10 and can be lifted out. The bearing for the tube 18 is a part of arm 17 of saddle 13. The left hand end of the jet tube 16 and the right hand end of the tube 18, both as shown in Figure 1, are provided with enlarged portions for the purpose of receiving a short length of flexible tubing to connect them into the system.

What is claimed is:

1. A spinning in unit for a tube spinning machine comprising a box, a transparent jet-tube unit, said tube having a yarn receiving mouth spaced from said jet, quick detachable means to support said unit within said box, a deflector having a yarn guiding groove therein and a hinged side wall of said box supporting said deflector for movement from a normal position above said unit with its groove leading to said mouth to a position affording visual and manual access to said unit.

2. A spinning in unit for a tube spinning machine comprising a box, a transparent jet-tube unit, said tube having a yarn receiving mouth spaced from said jet, quick detachable means to support said unit within said box, a deflector having a yarn guiding groove therein, opposite side walls of said box receiving said deflector therebetween, one of said walls being movable, said deflector being connected to said movable wall for movement therewith from a normal position above said unit with its groove leading to said mouth to a position affording access to said unit.

3. A spinning in unit for a tube spinning machine comprising a box, a jet-tube unit, said tube having a yarn receiving mouth spaced from said jet, quick detachable means to support said unit within said box, a deflector having a groove for guiding yarn to said mouth during spinning in, opposite side walls of said box normally receiving said deflector therebetween, one of said side walls being movable and the other fixed, detachable means interconnecting said walls to hold the movable one from the fixed one, said deflector being fixed to said movable wall for movement from the normal position with the deflector groove leading to the mouth of the tube to a position affording access to said unit.

4. A spinning in unit for a tube spinning machine comprising a box, a jet-tube unit, said tube having a yarn receiving mouth spaced from said jet, quick detachable means to support said unit within said box, a deflector having a groove for guiding yarn to said mouth during spinning in, opposite side walls of said box normally receiving said deflector therebetween, one of said side walls being hinged and the other being fixed, a rod type guide for guiding yarn to said mouth after spinning in, said guide passing through and interconnecting said opposite walls, resilient quick detachable means on said guide for holding said hinged wall from said fixed one in normal position, said deflector being attached to said hinged wall so that when said opposite walls are in normal position it lies above said unit with its groove leading to said mouth and is movable with said hinged wall to afford access to the unit.
